UNITED STATES PATENT OFFICE.

ELLIS W. FOX, OF VANCOUVER, BRITISH COLUMBIA, CANADA.

FIRE-PROTECTION DEVICE FOR CINEMATOGRAPH-MACHINES.

1,130,079.

Specification of Letters Patent.

Patented Mar. 2, 1915.

Application filed December 5, 1913. Serial No. 804,888.

To all whom it may concern:

Be it known that I, ELLIS W. FOX, a citizen of the Dominion of Canada, residing at Vancouver, in the Province of British Columbia, Canada, have invented certain new and useful Improvements in Fire-Protection Devices for Cinematograph-Machines, of which the following is a specification.

This invention relates to a device for automatically closing the beam and viewing apertures of a cinematograph operator's room in the event of the film catching fire.

Owing to the particularly inflammable nature of the film, municipal authorities and the fire underwriters require that every precaution be taken to confine the fire within the operator's room, and avoid unnecessary alarm or panic, in furtherance of which object the apertures from the room into the auditorium are closable with metal shutters that may be dropped in the event of fire.

It is the object of this device to close these shutters automatically if the film in passing through the machine catches fire adjacent to the magazine.

The essential feature of the invention lies in the use of an electrical means to operate the latch release mechanism of the shutters.

Although specifically designed to close the shutters the same provision is also available for performing any other operation of safety precaution, such as the releasing of any mechanism to close the metal box or place where extra reels of film are kept, the releasing of any mechanism used for opening windows or ventilators, in operating room, the closing of call bell circuit used for calling for assistance, the releasing of any mechanism for turning on the lights of the auditorium, etc.

The invention is particularly described in the following specification, reference being made to the drawings by which it is accompanied, in which:

Figure 1 is a vertical section through the device showing more or less diagrammatically the battery, the electromagnet and its circuit by which the mechanism is controlled. Fig. 2 is a front elevation of the end of the magazine showing the same without the battery and electromagnet. Fig. 3 is a perspective view of the circuit closing device detached. Fig. 4 is a diagram of the circuit. Fig. 5 is a face view showing the electromagnet and the mechanism by which the movement of its armature controls the

shutter closing. Fig. 6 is an enlarged perspective view of the shutter release bar, and Fig. 7 is a cross section of the shutter release on a vertical line through the viewing aperture.

In these drawings 2 represents the magazine within which is mounted the reel from which the film 3 is unwound for transmission past the beam of light from the lamp, 4, the axis of which beam is represented by 4, and 5 is the loose loop providing for the intermittent movement of the film past the light. This loop 5 is protected from the light from the lamp by an upper loop guard, 70 but as ignition of the film is most likely to occur at the exposure to the light beam 4, the loop 5 will afford the principal supply of film to feed a flame. For this reason a position immediately above the loose loop 5, 75 that is below the back lower corner of the magazine 2 is selected for the location of the safety fuse, the release of which under heat or flame is designed to effect the closing of the wall aperture shutters, or perform any other operation or operations which may be considered necessary.

Secured on the lower back end of the film magazine 2 is a base plate 10, the lower end of which is bent under the back corner of the magazine and is apertured, as shown in Fig. 3, leaving an end bar 11 for the attachment of the safety fuse. Pivotedly mounted at 12 to the vertical part of the base plate 10 is a clamp lever 13, having a coil spring 14 on its pivot, which spring acts to move the lever into the position indicated by the dot and dash lines in Fig. 1, and by the full lines in Fig. 3. The lower end of this lever 13 is outwardly bent and doubled back, as 15, and through this doubled end passes a small bolt having a wing nut 16. This forms a clamp on the end of the lever 13 which grips the ends of a loop 17 of readily inflammable material, such as film, from which the emulsion has been removed. This loop 17 holds the lever 13 in the position shown by the full lines in Fig. 1, and in the event of the film 5 igniting the flame from it immediately ignites the fuse loop 17 and releases the lever 13 which springs out to the position represented in Fig. 3, or by dot and dash lines in Fig. 1.

Where the use of film as a safety fuse is objected to by fire underwriters, or by by-laws governing any particular locality, a provision is made for the application of a

metallic safety fuse link 18 between a pin 19 projecting from the bar 11 and a hook member 20 secured on the lever 18. A fuse link may be used which will separate under the action of flame by the burning of loop 5, or from an excessive heat from any other source. A fuse link may be used, the melting temperature of which is in accord with the regulations of the district in which the invention is to be used.

While the fusible members 17 and 18 may be used alternatively, they may be also used conjunctively, if desired.

The upper end of the lever 13 projects beyond its pivot and is bent outward, as at 21, in Figs. 1 and 2. Projecting into the path of movement of this end 21 are the ends of two resilient contacts 22 which form the terminals of a battery circuit 23 and are secured on suitable insulation on the base plate 10 and are insulated from one another. The ends of these contacts 22 are so shaped and adjusted as to allow the end 21 of the lever 13 to contact with them during a sensible part of its movement, thus closing the circuit 23 only during such movement, that is, the end 21 is clear of the contacts 22 at both extremes of its movement but contacts with them and connects together to close the circuit while passing between these extremes. This insures that the battery circuit 23 is open when the fuse strip or link is in place, and ready for use, and also when the fuse is disconnected and the lever 13 is at the further limit of its movement under the action of its spring. The circuit 23 is closed only in moving from one position to the other and therefore the battery cannot be wasting, if for any reason the fuse has either been released or has not been connected.

In the battery circuit 23 is the coil of an electromagnet 24, the armature of which is mounted on the end of a pivoted lever 25. The movement of this armature, when the electromagnet is energized by the closing of the circuit 23, effects the release of the mechanism which sustains the aperture shutter of the operating room or any other precautionary mechanism which may be considered necessary, as stated in the preamble to this specification.

In the drawing herewith, the armature lever 25 is shown as sustaining the end of a lever 26 which is pivoted at 27 and on which is carried a weight 28, which is flexibly connected by a loose line, or by a chain 29 to one end of a bell crank lever 30, which is pivoted at 31 to the wall of the operating room. The other arm of this bell crank is pin-connected at 32 to a bar 33 which is endwise slidable in guides 34 secured to the wall in which are the several apertures to the auditorium. The shutter 35 of each aperture has a rod 36 projecting upward from it which rod has a hook-like projection 37

which is designed to engage and suspend the shutter on the upper edge of the bar 33, when that bar is in its normal position in which it is retained by a coil spring 41 connected to the bell crank lever arm or to the bar itself. Adjacent to the place of suspension of 37 on the bar 33 the upper corner of the bar is removed, as at 38, so that when the bar is endwise moved by the fall of the weight 28 the removed corner 38 is moved under the hook end 37 of the shutter rod 36, when each shutter falls of its own weight and closes its wall aperture of the operating room. The movement of the bar 33 may be limited within the range required by the angular movement of the bell crank lever 30 between the adjacent guide 34 and a stop 39 secured to the wall.

To facilitate the raising and hooking of the shutter rods 36 on the bar 33, a guide member 40 of thin sheet metal, bent to the required form, is attached to the wall adjacent to the place of suspension of each rod 36, which guide member directs the upper end 37 of the rod into its proper place.

To enable the circuit 23 to be closed at any time by the operator, or by an inspector, to test the shutter operating mechanism, a push button 42 is attached to the upper end of the base plate 10 and arranged in a shunt 43 of the circuit 23, as shown in Fig. 2 and in the diagram, Fig. 4.

I do not desire to be confined to the particular construction here set forth of operating the shutter closing mechanism, but desire protection on the automatic thermal or ignition released circuit closing device by which any precautionary safety mechanism may be operated. The ignition fuse is preferred as the danger is most frequently experienced from the film igniting at, or adjacent to the lamp exposure, but the device can be used for either one or both.

The arrangement of the fuse over the loose loop 5 and the application of it to hold the contact lever 13—21 in a position wherein a circuit is open, but closable on release, is an effective construction. The use of a lever in the connection between fuse and contact is a convenient one to apply and is simple in construction.

Having now particularly described my invention, I hereby declare that what I claim as new and desire to be protected in by Letters Patent, is:

1. A circuit closing device for operating a safety appliance in conjunction with a cinematograph machine, said device comprising a base plate secured to the lower back of the film magazine of the machine, the lower end of which base plate is bent under the magazine and has provision for attachment to it of a thermal fuse, resilient contacts secured on suitable insulation on the base plate, a lever pivotally mounted

on the base plate adjacent to said resilient contacts, one end of which lever has provision for connecting to it the other end of the thermal fuse, the other end of said lever 5 having provision to engage and connect the resilient contacts during movement of the lever from one extreme of its movement to the other.

2. A circuit closing switch comprising a 10 base plate, one end of which is bent over to project away from the plane of the remaining portion of the plate, said plate having ears, a clamp lever having ears coöperating with said plate ears and a pivot pin 15 connecting said ears, said clamp lever having one end bent outwardly and back upon itself to form a clamp member, a bolt passing through said clamp member, and a fusible connection between said lever and said bent 20 extension of said base plate, and circuit terminal members insulated on said base plate and adapted to be engaged by said lever when said fusible connection is released, and means continuously tending to move said 25 lever to engage said circuit terminals.

3. A thermo circuit switch comprising a base plate having one end bent backwardly and slotted, a lever pivoted to said base plate and having a clamp member at its 30 lower end, a fusible body secured by said clamp member and passing through said

slotted portion of said base plate to hold said lever in one position, a spring continuously tending to move said lever to another position, contact members insulated and supported on said base member, said lever having a heel to engage said contact members when said lever is released, said lever having a hook portion to project into the slot of said base member and a fusible connection between said base member and said hook member. 40

4. A circuit closing switch comprising a base plate having an offset portion and having one end bent forwardly and apertured, 45 a lever pivoted to said offset portion and having a clamp member at its lower end, a fusible body secured by said clamp member and passing through said apertured portion of said base plate to hold said lever in one 50 position, a spring continuously tending to move said lever to another position, contact members insulated and supported on said base member, said lever having a heel to engage said contact members when said 55 lever is in one position.

In testimony whereof I affix my signature in presence of two witnesses.

ELLIS W. FOX.
